UNITED STATES PATENT OFFICE.

ANTONIO CHIARELLI, OF NEW YORK, N. Y.

PROPELLING, LIFTING, AND STEERING DEVICE FOR AIRSHIPS.

Application filed February 4, 1926. Serial No. 85,902.

This invention relates to improvements in the art of aerial navigation, particularly to means which may equally well be used to propel and manoeuvre lighter than air and 5 heavier than air crafts, such as dirigibles, balloons, aeroplanes or the like.

The invention has for an object the provision of an improved mechanism for oscillating the wings of an air ship, so as to 10 propel and lift the said air ship.

A further object of the invention is the provision of an improved mechanism to steer and lift said aircrafts, or to enable the 15 said air ship to sail at high or low altitudes and to facilitate the ascent and the descent of the same.

For further comprehension of the invention, and of the objects and advantages thereof, reference will be had to the following 20 description and accompanying drawings, and to the appended claims in which the various novel features of the invention are more particularly set forth.

Fig. 1 of the drawings, is a perspective 25 view of a dirigible air ship, showing my improved device attached thereto.

Fig. 2 of the drawings, is a fragmentary 30 central sectional view of the mechanism for oscillating the wings thereof.

Fig. 3 of the drawings, is a fragmentary 35 top plan view, partly in section, so as to expose certain working parts.

Fig. 4 of the drawings, is a sectional view 40 taken on the line 4—4 of Fig. 2.

Fig. 5 of the drawings, is a similar view 45 taken on the line 5—5 of Fig. 2.

Fig. 6 of the drawings, is a similar view 50 taken on the line 6—6 of Fig. 2.

Fig. 7 of the drawings, is an enlarged 55 fragmentary top plan view of the dirigible airship as shown in Fig. 1.

Fig. 8 is a detail view of the locking 60 mechanism.

Fig. 9 is a side elevational view, partly 65 in section showing a modification of my improved mechanism.

Fig. 10 is a sectional view taken on the 70 line 10—10 of Fig. 9.

Fig. 11 is a sectional view taken on the 75 line 11—11 of Fig. 9.

Fig. 12 is a top plan view of the locking 80 mechanism as used in connection with my mechanism.

Fig. 13 is a perspective view of a modified 85

wing reinforcing device as used in connection with my improved mechanism.

Fig. 14 is a sectional view taken on the line 14—14 of Fig. 13.

The dirigible air ship 10, comprises 90 buoyant, or lighter than air qualities, due to the use of helium, or any suitable gas, and is provided with the common ordinary equipment as generally used for the welfare of the navigators and passengers thereof.

For propelling the dirigible air ships 10, 95 I have provided a plurality of wing members 11 and 11', pivotally attached to wing frames 12, as at 13, and connected to each other by rods 12'. The inner wing members 11' are provided with pinions 14, rigidly 100 attached to the rods 15, which are pivoted on frames 12 as at 15'. The wing frames 12, are pivoted at their inner ends to supporting members 17. A rod 16 is pivotally attached to the supporting member 17. The 105 said pinions 14, mesh with the pinions 18, which are rigidly attached to the rod 16 which has also rigidly attached thereto a pinion 19 which meshes with the sector 20, which is attached to a pin 21, and pivots 110 in the bearing 22 supported by the arm 23, attached to the supporting member 24. The sector 20 has an extended arm 25, which is attached by means of a pin and slot connection as at 26, to a disc 27, at or near its 115 periphery. The disc 27 is rigidly attached to the jack shaft 28, rotatively mounted in the bearings 29, suitably supported by the extended arms 30, of the said supporting member 24. The bevel gear 31 is rigidly 120 attached to the jack shaft 28, and meshes with the bevel pinion 32, rigidly attached to the motor shaft 33, which is rotatively 125 mounted in the bearings 34, and also supported by the supporting member 24, and 130 driven or rotated by the motor 35, which is of common ordinary construction such as commonly used for dirigible, air ships and the like. The above described construction being such as will permit the motor 35, 135 to oscillate the wing frames 12 and wings 11 and 11' with frame 12. It being understood that the wing members 11, and the inner wing members 11', will be held in a closed position, as shown in Figs. 1 and 140 2 of the accompanying drawings, when the said wing members 12' are oscillated in a backward direction which will propel the

dirigible air ship 10 and that the said wing members 11, and the said inner wing members 11' will be in an open position when the wing frame is oscillated in a reverse 5 or return direction.

One of the said pinions 18 has rigidly attached thereto a face cam 36. The locking rod 37, is a slidable fit in the bearing 38, and has rotatively attached at its lower extremity a cam roller 39, so located, as to cause the locking rod 37 to rise and fall when the heretobefore mentioned wing frames are oscillated. The upper or free extremity of the locking rod 37, is so positioned as to engage and disengage the lock 40, with the wing frame 12, so as to hold the said wing frame 12 while the inner wing member 11' and the said wing members 11 assume their relative positions. It is readily seen that 10 with the frame held stationary, and gears 18 turning gears 14, the wing member 11' will be caused to open, and rods 12' communicating this motion to wings 11. Thereafter the latch releases the frame, and the frame member moves forward. As the gears 18 reverse 15 their direction of rotation, meshing gears 14 cause the wings 11', 11 to close, thereafter forcing the frames 12 backward.

As a means of limiting the oscillations of 20 the above mentioned frame mechanism, I have provided bumpers 41, slidably mounted in the said dirigible air ship 10, as clearly shown in Fig. 7 of the accompanying drawing, and normally held in extended positions 25 by the springs 42; it being understood that the said bumpers 41 are suitably positioned so as to strike the oscillating mechanism.

In order to provide lateral movement of 30 the above mentioned mechanism viz, the motor and the frame device, I have provided a hand wheel 43, rigidly attached to the shaft 44, which is rotatively mounted in the bearing 45, supported by any convenient portion or part of the said dirigible air ship 35 10, the sprocket wheel 46 is rigidly attached to the said shaft 44, and the sprocket chain 47 is extended over the said sprocket wheel 46 and the sprocket wheel 48, which is rigidly attached to the lead screw 49, rotatively 40 mounted in the bearing 50 supported by the base 51 for the motor, which is fastened to the ship, the threaded arm 52 engages with the lead screw 49 and is rigidly attached to the sub-frame 53 of the base 51. The hand 45 wheel 43 when rotated in either direction will move the said supporting member 24 laterally in either direction.

In order to rotate the above mentioned 50 mechanism, I have provided a suitable crank handle 54, or hand wheel, attached to the sprocket wheel 55, which is rotatively mounted in the support 56, attached to the sub-frame 53, the sprocket chain 57, is extended over the said sprocket wheel 55 and 55 the sprocket wheel 58, which is rigidly at-

tached to the shaft 59, rotatively mounted in the bearings 60, supported by the sub-frame 53. The said shaft 59, has rigidly attached thereto a worm 60', meshing with a worm wheel 61, or teeth cut on the periphery of the 70 said supporting member 24, it being understood that the supporting member 24 is of hollow cylindrical construction, and is rotatively supported by a plurality of rollers 62, 75 rotatively mounted in supports 63 attached to the sub-frame 53, which is slidably engaged with the frame proper 64, as at 65.

Referring in particular to Figs. 9, 10, 11 and 12, of the accompanying drawings, in which I have shown a modification of my 80 improved mechanism. The said pinion 19, meshes with a sector 66, pivotally attached to the pin 67, supported as at 68, and has an extended arm 69, engaging with the extended extremities 70, of the dog 71, pivoted 85 as at 72, and provided with inner extended extremities 73, having rotatively attached thereto rollers 74, engaging with the eccentric 75, attached to the said motor shaft 33, allowing the motor shaft 33 to oscillate 90 the said wing frames 12.

As a means of increasing or decreasing the amount or angle of oscillations, I have provided a hand wheel 76, attached to the shaft 77, rotatively mounted in suitable bearings 78, the worms 79 are rigidly attached thereto, and mesh with the worm wheels 80, which are attached to the lead screws 81, which engage with the supports 82, as at 83, it being understood that the said wing frames 100 are pivotally attached to the said supports 82. The extended arms 69 of the sector 66 swings from 67 as a center, and the distance from the dogs 73 to the pivot 67 determines the amount of oscillation distance, or 105 amplitude. Sliding pins 81' are secured to support 82 and are adapted to engage in corresponding cars 81^a to permit of varying the distance between the dogs 73 and the pivot point 67.

Referring in particular to Figs. 13 and 14 of the accompanying drawings, the said wing frames 12, are provided with extended portions 84, oppositely located thereto, and here attached thereto, a flexible member 85, which is extended over the pulleys 86, rotatively attached to any suitable portion of the said dirigible airship 10, the said flexible member is also extended over and wound around the pulley 87, which is rigidly attached to the said second vertical rod 16. Thus rigidity is added to the frame 12.

It will be understood that the hereinbefore described oscillating wing members 11 and 11', may be located at the front of a dirigible air ship or any other suitable positions. It being further understood that the said oscillating wing members when oscillated in a rearward direction will tend to cause a partial vacuum at the front of the ship or re- 130

move the air adjacent to the said oscillating members which will permit to pull the ship forward, as is common to tractor types of dirigible air ships and the like. It being 5 also understood that a plurality of sets of horizontal wings may be operated all along the ship structure.

Having thus described my invention, what I claim as new and desire to protect by 10 Letters Patent of the United States is as follows:

1. In a device of the class described, having pivotally mounted frame members pivotally supporting wing members, the inner 15 wing members having gears coaxially mounted to its pivot, and a motor having an eccentric on the end of its shaft, the combination of a shaft, gears on said shaft meshing with said gears, a support, a gear sector pivoted to said support, said gear sector being formed with an extended arm, another gear 20 on said shaft meshing with said sector, another support, a dog pivoted to said support, one end of said dog engaging said eccentric, 25 the other end engaging said extended arm, and means for changing the distance between said supports.

2. In a device of the class described, having pivotally mounted frame members pivotally supporting wing members, the inner wing members having gears coaxially mounted to its pivot, and a motor having an eccentric on the end of its shaft, the combination of a shaft, gears on said shaft meshing with said gears, a support, a gear sector pivoted to said support, said gear sector being formed with an extended arm, another gear 30 on said shaft meshing with said sector, another support, a dog pivoted to said support, one end of said dog engaging said eccentric, the other end engaging said extended arm, and means for changing the distance between said supports, said means comprising 35 bearings, a shaft mounted in said bearing, a hand wheel on one end of said shaft, worms mounted on said shaft, worm wheels meshing with said worms, lead screws attached to said worm wheels, and lead screw engaging 40 said supports.

3. In a device of the class described, having pivotally mounted frame members pivotally supporting wing members, the inner wing members having gears coaxially mounted to its pivot, and a motor having an eccentric on the end of its shaft, the combination of a shaft, gears on said shaft meshing with said gears, a support, a gear sector pivoted to said support, said gear sector being formed with an extended arm, another gear 45 on said shaft meshing with said sector, another support, a dog pivoted to said support, one end of said dog engaging said eccentric, the other end engaging said extended arm, and means for changing the distance between said supports, said means comprising 50

bearings, a shaft mounted in said bearings, means for manually turning said shaft, worms mounted on said shaft, worm wheels meshing with said worms, lead screws attached to said worm wheels, said lead screw 55 engaging said supports.

4. In a device of the class described, having pivotally mounted frame members pivotally supporting wing members, the inner wing members having gears coaxially mounted to its pivot, and a motor having an eccentric on the end of its shaft, the combination of a shaft, gears on said shaft meshing with said gears, a support, a gear sector pivoted to said support, said gear sector being formed with an extended arm, another gear 60 on said shaft meshing with said sector, another support, a dog pivoted to said support, one end of said dog engaging said eccentric, the other end engaging 65 said extended arm, and means for changing the distance between said supports, said means comprising bearings, a shaft mounted in said bearing, worms mounted on said shaft, worm wheels meshing with said worms, lead screws attached to said worm 70 wheels, said lead screw engaging said supports.

5. In a device of the class described, associated with an airship, the combination of a base slidably mounted to said air ship, an arm depending from said base, a lead screw threadedly engaging said arm, said lead screw being rotatively supported, manual means for turning said lead screw, a 95 supporting member rotatably mounted on said base, manual means for rotating said supporting member, a motor mounted in said supporting member, frame members pivotally mounted to said supporting member, wing members mounted in said frame members, and means for connecting said motor with said frame and wing members, to cause an oscillating motion of said frame and wing members.

6. In a device of the class described, associated with an airship, the combination of a base slidably mounted to said airship, an arm depending from said base, a lead screw threadedly engaging said arm, said lead screw being rotatably supported to said airship, manual means for turning said lead screw, said means comprising a sprocket wheel fixed to said lead screw, a sprocket chain engaging said sprocket wheel, another 100 sprocket wheel engaging said sprocket chain, a shaft suitably supported supporting said last mentioned sprocket wheel, and a hand wheel on said shaft, a supporting member rotatably mounted on said base, manual means for rotating said supporting member, a motor mounted in said supporting member, frame members pivotally mounted to said supporting member, wing members mounted 105 in said frame members, and means for con-

necting said motor with said frame and wing members, to cause an oscillating motion of said frame and wing members.

7. In a device of the class described, associated with an airship, the combination of a base slidably mounted to said airship, an arm depending from said base, a lead screw threadedly engaging said arm, said lead screw being rotatably supported, manual means for turning said lead screw, a supporting member rotatably mounted on said base, being guided on a plurality of rollers supported from said base, manual means for rotating said supporting member, a motor mounted in said supporting member, frame members pivotally mounted to said supporting member, wing members mounted in said frame members, and means for connecting said motor with said frame and wing members, to cause an oscillating motion of said frame and wing members.

8. In a device of the class described, as-

sociated with an airship, the combination of a base slidably mounted to said airship, an arm depending from said base, a lead screw threadedly engaging said arm, said lead screw being rotatably supported, manual means for turning said lead screw, a supporting member rotatably mounted on said base, manual means for rotating said supporting member, said last mentioned means comprising teeth formed on the periphery of said supporting member, a worm meshing with said teeth, and means to rotate said worm, a motor mounted in said supporting member, frame members pivotally mounted to said supporting member, wing members mounted in said frame members, and means for connecting said motor with said frame and wing members, to cause an oscillating motion of said frame and wing members.

In testimony whereof I have affixed my signature.

ANTONIO CHIARELLI.
